ROTATABLE ANTENNA FOR TELEVISIONS

Filed Dec. 11, 1948

UNITED STATES PATENT OFFICE

2,642,754

ROTATABLE ANTENNA FOR TELEVISIONS

Maurice P. De Conti, New Britain, Conn.

Application December 11, 1948, Serial No. 64,849

1 Claim. (Cl. 74—504)

1

This invention relates to radio beam antennas, and more particularly to an antenna support which is rotatable, whereby the antenna may be readily turned so as to receive radio signals efficiently from any point of the compass.

One object of this invention is to provide a device of the above nature which is adapted to support an antenna at a high elevation without danger of breaking or overturning.

Another object is to provide a device of the above nature wherein the antenna may be accurately adjusted without backlash and will remain in any position in which it is placed by the operator.

Another object is to provide a device of the above nature wherein the weight of the antenna and its support will be carried by a single thrust bearing adjacent the bottom of the support, whereby complicated foundation structures will be avoided.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawing,

Fig. 1 is a perspective view of the improved antenna as it would appear when installed upon a house.

Fig. 2 is a longitudinal sectional view of the bearing 18, showing portions of the vertical pipe and a guy wire connected to the bearing housing.

Referring now to the drawing, the numeral 10 indicates a directional antenna, which may be of any suitable type, as herein shown comprising a vertical stem 11 which is firmly secured upon the upper end of a vertical supporting shaft in the form of a length of metal pipe 12. The shaft or pipe 12 extends downwardly through a roof 13 of a house 14, and is supported thereon by means of a base 15 having a thrust ball bearing or other substantially frictionless bearing 16 secured to the pipe 12.

In order to hold the pipe 12 firmly in vertical position, provision is made of a plurality of ball bearings 17, 18, 19, which are secured at spaced points along said pipe.

The bearings 17 and 18 are braced by means of sets of guy wires 20, 21, respectively, which are attached to the building structure at suitable spaced points, as shown. The bearing 19 is rigidly secured to one end of the building 14 by means

of an angle iron 22 having a U-strap 22a which embraces said bearing 19.

In order to permit the antenna 10 to be manually turned to any desired point of the compass, the lower end portion of the pipe 12 is provided with a handle in the form of a cross piece 23 which is disposed in a readily accessible location below the roof 13, and is preferably formed from pipe fittings.

10 A uniform frictional restraint upon the rotation of the pipe 12 is imposed by means of a set screw 23a which is mounted in the angle iron 22 in alignment with said pipe. This restraint is sufficient to prevent accidental turning of the antenna 10 in the wind. Inasmuch as the bearings 16, 17, 18, and 19 are substantially frictionless, the frictional restraint provided by the set screw 23a will result in uniform operation of the pipe 12, thus avoiding inaccuracies in the adjustment of the antenna such as might arise from lost motion or resilient twisting of the pipe 12.

The antenna 10 is provided with the usual lead-in wires 24, which are passed inwardly through an aperture 25 in the side of the antenna stem 11, and thence downwardly through the pipe 12, and outwardly through an apertured pipe cap 26 below the cross piece 23.

30 The pipe 12 preferably is grounded by means of a wire 27 in order to avoid any accumulation of static electricity thereon, and also permitting said pipe to serve as a lightning rod.

As shown in Fig. 2, the bearing 18 is of the type which contains a series of balls 28 confined in grooved inner and outer races 29, 30. The bearing 18 is supported by means of a collar 31 secured to the pipe 12 by a pin 32, and is provided with an inverted housing 33 having an apertured flange 34 for the attachment of the guy wires 21. It will be understood that the housing 33 is supported upon the stationary outer race 30, and is preferably provided with a weatherproof upper closure in the form of a flanged disk 35 which is sealed to and rotatable with the pipe 12. The bearing 17 preferably has a structure identical to the bearing 18.

45 It will be understood that the directional antenna 10 may be installed at substantially any desired height, merely by making the pipe 12 of the desired length, and by installing as many spaced bearings, such as the bearings 17, 18, as may be necessary to maintain the pipe 12 firmly in position—all of the bearings being firmly anchored by means of guy wires.

Operation

55 The invention herein disclosed will be found particularly useful for picking up high-frequency

radio signals such as are employed in television and frequency-modulation broadcasting.

The lower end of the lead-in wire 24 will, of course, be connected to a suitable radio receiver, and when tuning the receiver to a particular radio station, it will only be necessary for the operator to rotate the antenna 10 by means of the handle or cross piece 23 until the most efficient reception is obtained.

One advantage of the invention herein disclosed is that the antenna may be easily and accurately adjusted without lost motion or backlash.

Another advantage is that the supporting means for the antenna is relatively inconspicuous, inasmuch as the efficient bracing afforded by the ball bearings and the guy wires will permit a relatively thin shaft or pipe to be used.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all modifications and embodiments coming within the scope of the following claim.

Having thus fully described the invention, what is claimed as new, and for which it is desired to secure Letters Patent, is:

In a rotatable antenna support, an elongated

lightweight slender vertical shaft of flexible material adapted to extend through the roof of a building, a thrust bearing rotatably embracing and supporting said shaft adjacent the lower end thereof, a plurality of bearings arranged at spaced intervals along the length of said shaft for preventing the bending or collapse of said shaft, means secured to said bearings for connection to roof of said building at spaced points around said shaft, an operating handle at the lower end of said shaft, and means located at an intermediate point on the length of said shaft to exert a uniform frictional restraint against accidental rotation thereof.

MAURICE P. DE CONTI.
